his Attorney

UNITED STATES PATENT OFFICE.

HARRY W. YOUNG, OF CHICAGO, ILLINOIS.

ELECTRICAL FUSE.

1,228,354.

Specification of Letters Patent.

Patented May 29, 1917.

Application filed September 26, 1914. Serial No. 862,690.

To all whom it may concern:

Be it known that I, HARRY W. YOUNG, a citizen of the United States, and a resident of the city of Chicago, county of Cook, and State of Illinois, have invented certain new and useful Improvements in Electrical Fuses, of which the following is a specification.

My invention relates to improvements in electrical fuses and more especially to removable fuse cartridges for such constructions, the object of the invention being to provide a simple and efficient construction of this character which is capable of economical manufacture.

The invention consists in the combinations and arrangements of parts hereinafter described and claimed.

The invention will be best understood by reference to the accompanying drawing forming a part of this specification, and in which—

Figure 1 is a view of a fuse member embodying my invention, taken on substantially line 1—1 of Fig. 2,

Fig. 2, a central longitudinal section of the fuse member,

Fig. 3, a section taken on line 3—3 of Fig. 2,

Fig. 4, a perspective view of a fusible member employed in the construction, and

Fig. 5, a face view of one of the end plates employed in the construction.

The preferred form of construction as illustrated in the drawing comprises a tube 6 of insulating material having metallic end plates 7 and 8 inserted within the ends thereof. Each of these plates is provided with teeth 9 on its edges and is secured in position by pressing a metallic cap 10 over the corresponding end of tube 6. This cap is pressed over the end of tube 6 with sufficient force to embed the teeth 9 in said tube and also to embed the sides of the cap in said tube as indicated. Besides generally reinforcing the ends of tube 6, the plates or disks 7 and 8 afford sufficient resistance to the pressure employed in forcing caps 10 into place which is quite considerable. A fusible strip 11 is arranged in tube 6 and is provided with a central recess 12 in one end, the adjoining portions 13 of said end being soldered to plate 7. At its other end strip 11 is extended through slots 14 in plate 8 and the corresponding cap 10 and is bent outwardly and

rearwardly to form an end 15 overlapping the end of tube 6.

Tube 6 is incased in an outer tube 16 also of insulating material but preferably of a more permanent nature, and one end of tube 16 is permanently closed by means of a metallic cap 17 secured thereto. A securing screw 18 is swiveled in cap 17 and threaded in plate 7 to serve as a means for binding the cartridge in tube 16, recess 12 receiving the end of said screw as indicated. A guard pin 19 is also provided for screw 18 and an opening is provided in plate 7 to receive said pin, thus guarding against substitution of a fuse cartridge of different capacity. The other end of the tube 16 is closed by a metallic band 20 and a metallic plate 21 having projections 22 and 23 resting adjacent said band. Plate 21 also carries a binding screw 24 which is adapted to pass through an opening 25 in the end 15 of fusible member 11 and serve as a means for securing said end and effecting good electrical connection therewith.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A fuse comprising a tube; a disk inserted in the end of said tube; a cap pressed over the end of said tube, the edges of said disk being embedded therein; a fusible member in said tube; and means for effecting electrical connection with the ends of said fusible member, substantially as described.

2. A fuse comprising a tube of insulating material; a metallic disk inserted in the end of said tube; a metallic cap pressed over the end of said tube, the edges of said disk being embedded therein, a fusible member in said tube; and means for effecting electrical connection with the ends of said fusible member, substantially as described.

3. A fuse comprising a tube; a disk in-

110

serted in the end of said tube and having teeth on its edges; a cap pressed over the end of said tube, said teeth being embedded therein; a fusible member in said tube; and 5 means for effecting electrical connection with the ends of said fusible member, substantially as described.

4. A fuse comprising a tube of insulating material; a metallic disk inserted in 10 the end of said tube and having teeth on its edges; a metallic cap pressed over the end of said tube, said teeth being embedded therein; a fusible member in said tube; and means for effecting electrical connection 15 with the ends of said fusible member, substantially as described.

5. A fuse comprising a tube of insulating material; a convex metallic disk inserted within each end of said tube and 20 having teeth on its edges; a metallic cap pressed over each end of said tube, said teeth being embedded therein; a fusible member within said tube having one end soldered to one of said disks and the other 25 end passing through the disk and cap at

the corresponding end of said tube; and means for effecting electrical connection with said protruding end of said fusible member and with the disk at the other end thereof, substantially as described.

30

6. A fuse comprising a tube of insulating material; a convex disk inserted within the ends of said tube; a metallic cap pressed over each end of said tube embedding the edges of said disks therein; a fusible member in said tube; and means for effecting electrical connection with the ends of said fusible member, substantially as described.

35

7. A closure for the end of a fuse tube comprising a convex disk inserted therein and embedded in the walls thereof, substantially as described.

40

In testimony whereof I have signed my name to this specification in the presence of two subscribing witnesses.

HARRY W. YOUNG.
